UNITED STATES PATENT OFFICE.

NORMAN L. PRICE, OF LYNCHBURG, VIRGINIA.

IMPROVEMENT IN FUNNELS.

Specification forming part of Letters Patent No. 118,051, dated August 15, 1871.

To all whom it may concern:

Be it known that I, NORMAN L. PRICE, of Lynchburg, in the county of Campbell and State of Virginia, have invented a new and Improved Funnel; and I do hereby declare that the following is a full, clear, and exact description thereof, which will enable others skilled in the art to make and use the same, reference being had to the accompanying drawing forming part of this specification.

This invention relates to improvements in funnels, and it consists in having a top or cover on the funnel with holes adapted for supporting the different measures used, bottom up, with the open ends entering said holes to drain and exclude flies and other insects and dirt.

The drawing is a perspective view of the improved funnel, partly sectioned.

A is an ordinary funnel, to which I propose to apply a cover, B, preferably raised a little above the top by a vertical band or rim, C, with holes in

it of different sizes adapted to receive the measures D by their upper ends, said measures being inverted as the liquid is poured in through the hole adapted to the measure being emptied and entered in its hole, as shown, to be supported thereat for drawing and closing the funnel against the admission of insects or dirt while not in use.

The funnel is more particularly applicable for molasses and other liquids which flow sluggishly, but may be used for any.

Having thus described my invention, I claim as new and desire to secure by Letters Patent—

The funnel A, provided with a cover, B, having holes adapted for receiving and holding the measures D and used therewith, all substantially in the manner specified.

NORMAN L. PRICE.
